OFFICE CABINET HAVING SHELF-FORMING CLOSURES

Ray D. Hinton, Oak Park, Ill.

Application September 5, 1944, Serial No. 552,786

1 Claim. (Cl. 312—161)

(Granted under the act of March 3, 1883, as amended April 30, 1928; 370 O. G. 757)

1

The invention described herein may be manufactured and used by or for the Government for governmental purposes, without payment to me of any royalty thereon.

This invention relates to a collapsible office unit, and more particularly to a collapsible combined desk and file cabinet which also provides a typewriter support and a storage space for the typewriter when it is not in use.

It is frequently necessary to perform office work involving the use of a typewriter and a filing system under circumstances providing only very limited space or requiring frequent change of location; as for example in field work of various kinds. For such purposes it is highly desirable that the available work-surface and filing facilities be not only compact but also collapsible and readily portable; and this is especially difficult to achieve where a typewriter is involved.

The prior art provides numerous varieties of collapsible typewriter tables or typewriter desks, but they seldom include filing facilities of appreciable value, or if they do the unit as a whole is usually heavy and cumbersome, which mitigate against portability. Moreover, those units of existing design which do provide ample work space and filing facilities, in addition to accommodating the typewriter, usually do not lend themselves to disposal in a small space.

The present invention seeks to provide a combined desk and file cabinet which not only provides a typewriter support and a storage space for the typewriter when it is not in use; but one which is collapsible and self-contained whereby its portability and efficient storage is facilitated.

Another object is the provision of a device of the class described which consumes a minimum amount of space both when in use and in storage.

Another object is the attainment of the foregoing objectives by a design which is inexpensive to manufacture and quite durable in service.

The invention, then, comprises the features hereinafter fully described and as particularly pointed out in the claim, the following description and the annexed drawing setting forth in detail a certain illustrative embodiment of the invention, this being indicative of but one of a number of ways in which the principle of the invention may be employed.

In said drawings:

Figure 1 is a perspective of a collapsible office unit made in accordance with the teachings of the present invention, the same being shown in

operative position with the filing facilities in exposed relationship, and the typewriter support and the work-surface extended and respectively supporting a typewriter and a stationery cabinet.

Figure 2 is a perspective of the collapsible office unit in fully collapsed state, all of the instrumentalities described immediately hereinbefore being fully enclosed thereby presenting a compact structure and one made up entirely of substantially plane surfaces, whereby the unit may be readily transported or efficiently stored;

Figure 3 is a sectional elevation on the line 3—3 of Figure 1; and

Figure 4 is a sectional elevation on the line 4—4 of Figure 1.

Referring more particularly to the drawings, the unit of the present invention comprises a cabinet, the numerals 1 and 2 respectively designating the bottom and back members thereof while the side members are shown at 3 and 4. The bottom member 1 of the cabinet rests upon two cleats 5 which are attached to its underside, one lying immediately below each of the side members 3 and 4. This construction and arrangement permits the spacing of the bottom 1 from the ground or floor upon which the cabinet is to rest.

The front of the cabinet comprises a pair of upper and lower panels 6 and 7, respectively. The upper front panel 6 is rigidly connected to the two side members 3 and 4 while the lower front panel 7 is hingedly connected as at 8 to the front panel 6.

Referring to Figs. 1 and 4, it will be perceived that the upper front panel 6 is considerably shorter than the hingedly mounted lower front panel 7, whereby the latter may be pivotally moved into a horizontal plane at an elevation which will permit its use as a work surface.

Within the space enclosed by the hinged lower front panel 7 is a pair of spaced lower and upper horizontal partition members 10 and 11 which divide the cabinet into lower, intermediate and upper storage spaces.

Referring to Figs. 3 and 4, the inner surfaces of the side members 3 and 4 are provided adjacent their bottoms with a pair of attached horizontal extending cleats 12 which form a pair of ways 13 for the reception of a slidably removable board 14 to which may be attached a typewriter 15 of standard design. Thus, the lower storage space may be utilized for the reception of a typewriter in the manner aforesaid.

Between the lower and upper horizontal par-

titions 10 and 11 is a vertical partition member 16 which divides the space into one which is divisible by means of a horizontal partition member 17 to receive upper and lower sliding drawers 20 and 21, respectively.

The space defined by the lower and upper horizontal partition members 10 and 11 and the vertical partition member 16 on its side opposite that which cooperates with the horizontal partition member 17 is undivided, whereby it may be used for the reception of miscellaneous office paraphernalia of substantial size (not shown).

The upper storage space of the cabinet (i. e. above the upper horizontal partition member 11) is provided with two series of spaced vertical partition elements, the said series being right-angularly disposed with respect to each other, as shown at 22 and 23. The series 22 extends fully between the side members 3 and 4 from adjacent the upper front panel 6 to a point about midway of the depth of the cabinet. The series 23 of spaced vertical partition elements extends between the back member 2 and the innermost element of the series 22 from adjacent the side member 4 to a point about midway of the width of the cabinet. This construction and arrangement provides a storage space of substantial size at the right-hand rear of the cabinet which may, if desired, be used to accommodate a removable stationery cabinet 25.

The side member 4 is cut away along its upper end to receive a short extension panel 28 to which there is connected in right-angular relationship the top 29 of the cabinet. The lower end of the panel 28 is hingedly connected, as at 30 to the upper end of the side member 4, whereby the top 29 of the cabinet may be swung outwardly to occupy an outboard horizontal plane in the manner illustrated in Figs. 1, 3 and 4. While in this outboard position the top 29 of the cabinet may support the board 14 and its attached typewriter 15, and when the lower front panel 7 is elevated to the horizontal, a typist may occupy a position at the typewriter with the said panel 7 at his immediate right to thereby provide a work-surface which is suitable for numerous purposes including the handy disposition of the stationery cabinet 25.

The lower front panel 7 and the top 29 of the cabinet may be sustained in the intermediate positions described by any suitable means. In connection with the lower front panel 7, one acceptable form of support is illustrated as comprising clips 32 having central recesses 33 for the reception of the ends of a supporting rod 34 having extremities of cross section corresponding to the contours of the said recesses. According to this embodiment the inner surface of the lower front panel 7 carries a clip 32 adjacent the center of its outer end while a similar clip is correspondingly disposed on the upper surface of the bottom 1 of the cabinet.

The top 29 of the cabinet may be supported by a pair of rods 36 having flattened and angularly extending ends 37 which seat in detents 38 in the surfaces of the side member 4 and the said top. These flattened and angularly extending ends 37 (of the rods 36) are retained in the detents 38 by means of small plates 39 which partially overlap the detents.

Referring to Fig. 2, it will be perceived that when the board 14 and the attached typewriter 15 are stored in the lower storage space of the cabinet, the stationery cabinet 25 stored in the storage space provided for it, and the lower front panel 7 and the top 29 are in their closed position, the cabinet assumes the shape of a box providing substantially plane surfaces which facilitate transportation and storage. The lower front panel 7 and the top 29 may be locked in closed position by means of the conventional latching devices 41; and carrying handles 42 may be attached to the side members 3 and 4.

Other modes of applying the principles of the invention may be employed, changes being made as regards the details described, providing the features stated in any of the following claim, or the equivalent of such, be employed.

Having thus described my invention, what I claim as new and wish to secure by Letters Patent is:

A cabinet adapted to enclose office equipment and to be extended to support said office equipment in position for use, said cabinet being substantially rectangular and having four vertical walls, all of said walls of said cabinet being substantially coextensive in height when said cabinet is closed, one of said walls being horizontally divided into a stationary lower portion and an upper portion hinged thereto and adapted to swing outwardly and downwardly to occupy a substantially vertical position, the cabinet having a top wall fixed to the outer end of the hinged upper portion of said horizontally divided wall whereby it may assume a horizontal position to form an outwardly extending shelf, the next adjacent right angularly extending wall being horizontally divided into a stationary upper portion and a lower portion hinged thereto and adapted for upward swinging movement into a horizontal position to form a second outwardly extending shelf, the bottom of said cabinet being connected to the lower edges of all but said second-named wall, and means for supporting both of said shelves in their outwardly extending positions, the horizontal position occupied by said first-named outwardly extending shelf being substantially lower than the top of the cabinet and the horizontal position occupied by said second-named outwardly extending shelf being substantially lower than that of said first-named outwardly extending shelf.
